(57) **CLAIM**

The ornamental design for a backpack as shown and described.

DESCRIPTION

The patent or application file contains at least one drawing executed in color. Copies of this patent or patent application publication with color drawing(s) will be provided by the Office upon request and payment of the necessary fee.

1. Backpack

1.1 : Perspective

1.2 : Front

1.3 : Back

1.4 : Left

1.5 : Right

1.6 : Top

1.7 : Bottom

1.8 : Reference

This design article is for carrying goods; four edges of the front part of the design are round and the top edge thereof is more round than the bottom edge thereof; the triangular and star-like ornaments expressed in reproductions 1.1, 1.2, 1.3, 1.6 to 1.8 are excluded from the scope of protection; reproduction 1.8 is a reference view showing the state in use of the claimed design and forms no part thereof.

1 Claim, 8 Drawing Sheets
